UNITED STATES PATENT OFFICE

STANLEY OBSTBAUM, OF BROOKLYN, NEW YORK

DESIGN FOR A SET OF PLAYING CARDS

Application filed June 20, 1930. Serial No. 36,114. Term of patent 14 years.

To all whom it may concern:

Be it known that STANLEY OBSTBAUM, a citizen of Russia, and resident of the city of New York, borough of Brooklyn, in the county of Kings and State of New York, has invented a new, original, and ornamental Design for a Set of Playing Cards, of which the following is a specification, reference being had to the accompanying drawing, forming part thereof, in which the figures are plan views of the face sides of the playing cards embodying my invention. The backs of the cards may be plain or of any conventional design.

I claim:

The ornamental design for a set of playing cards substantially as shown and described.

Dated, New York City, June 13th, 1930.

STANLEY OBSTBAUM.
